(57) **CLAIM**

The ornamental design for a television receiver, as shown and described.

DESCRIPTION

FIG. 1 is a perspective view of a television receiver showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a reference front elevational view thereof, showing a portion which is silver in color by hatching;

FIG. 9 is a reference cross sectional view thereof, taken along a line IX—IX of FIG. 8;

FIG. 10 is an enlarged view of a portion X of FIG. 8;

FIG. 11 is an enlarged view of a portion XI of FIG. 8; and,

FIG. 12 is a reference view of a television receiver, taken along a line XII—XII of FIG. 8.

The broken lines shown in drawings are for illustrative purposes only and form no part of the claimed design.
